PLATING MACHINE

Daniel J. Borodin, Detroit, Mich., assignor to Wagner Brothers, Inc., Detroit, Mich., a corporation of Michigan

Filed Aug. 14, 1957, Ser. No. 678,225

18 Claims. (Cl. 204—198)

This invention relates to plating machines and more particularly to plating machines of the type wherein rack supported work pieces are conveyed automatically through a succession of plating tanks, such as shown in my copending applications Serial No. 596,712, filed July 9, 1956, and Serial No. 664,840, filed June 10, 1957.

In a plating machine of the type disclosed in said copending applications, the work pieces to be plated are arranged on racks. These racks are suspended from carriers that are slidably mounted on cathode rails extending along each side of the tank structure of the machine. A carriage structure that reciprocates lengthwise of the tank structure is provided with pusher arms for sliding the carriers along the rails to successive stations within a tank and with an elevating mechanism for lifting the carriers from the last station of one tank and depositing them in the first station of the next successive tank.

In machines of this type, the anodes are usually supported within the plating tanks as by suspending them from anode bars that extend longitudinally of the plating tanks. In such an arrangement, the plating current is caused to flow from the cathode rails, through the carriers and the racks to the work pieces and through the plating solution to the anodes. Some work pieces, because of their shape, are difficult to plate with such an arrangement because the anodes are not desirably located with respect to some surfaces of the work pieces. For example, work pieces having large concavities are difficult to arrange on the work racks so that all surfaces thereof are plated as desired.

An object of the invention resides in the provision of an economical and efficient auxiliary anode system for automatic plating machines of the type described.

Another object of this invention is to provide a plating machine of the automatic type which includes auxiliary anodes arranged on and movable with the work racks for plating work pieces which would be otherwise difficult to plate and including means for connecting such auxiliary anodes through the work carrier to an anode rail.

A further object of the invention resides in the provision of a work carrier having a pair of contact members electrically connected together and insulatively supported thereby and arranged to contact one with an auxiliary anode on the plating rack and the other with an auxiliary anode rail on the plating tank.

In the drawings:

Fig. 1 is a fragmentary sectional view of a plating machine embodying the present invention.

Fig. 2 is a fragmentary sectional view taken along the lines 2—2 in Fig. 1 with parts broken away.

Fig. 3 is an end elevational view with parts broken away of a portion of the apparatus shown in Fig. 1.

Fig. 4 is a top plan view of the auxiliary hook on the carrier illustrated in Figs. 1 and 2.

Fig. 5 is a fragmentary perspective view of the anode bars and rail arrangement of the plating tank.

2

Fig. 6 is a fragmentary perspective view, with parts broken away, showing the mounting for the combined anode bar and rail clamp on the plating tank.

Fig. 7 is a diagrammatic perspective view of the work rack.

In Fig. 1 of the drawing, there is illustrated a fragment of a plating machine according to the present invention which includes a plating tank 10 along the sides of which are mounted anode bars 12 and cathode rails 14. Only one anode bar 12 and one cathode rail 14 are illustrated in Fig. 1. Normally, the machine includes a pair of anode bars 12 and a pair of cathode rails 14, one along each side of the tank. A pair of such anode bars 12 are illustrated in Fig. 5. Cathode rails 14 are insulatively supported from the side edges of the tank 10 in any suitable manner. These cathode rails are arranged to slidably support work carriers 16. In Fig. 1 of the drawings, only a portion of work carrier 16 is illustrated. Carrier 16 includes a pair of castings 18 which are interconnected by a transversely extending bar 20. Castings 18 are secured to the opposite ends of bar 20 by means of caps 22 and screws 24. Each casting 18 includes a shoe 26 that is slidably arranged on the upper edge of the cathode rails 14.

Referring now to Fig. 2, it will be observed that at the center of transverse bar 20, there is secured a casting in the form of a yoke 28 that is provided with a pair of depending hook members 30. Yoke 28 is secured to bar 20 by means of a cap 32 and screws 34 provided with nuts 36. The hooks 30 are arranged to engage with the transverse bar 38 at the upper end of a work rack 40 (Fig. 7) to support the work rack in the plating tank. Rack 40 is provided with fastening members 42 fashioned as spring clips or the like for holding work pieces 44 to be plated. The work pieces 44 illustrated are each provided with a concave face 46. Normally, it would be difficult to plate the concave face 46 solely by the provision of anodes 48 suspended from the anode bars 12 along each side of the machine. Thus, the rack 40 illustrated is provided with an auxiliary anode 50. Anode 50 is insulatively mounted on rack 40 and is electrically connected by a strap 52 with a sleeve 54 fixed on transverse bar 38 intermediate the ends thereof. Sleeve 54 is electrically insulated from bar 38 by an insulating sleeve 56 (Fig. 2).

Intermediate the hooks 30 on yoke 28, there is supported an auxiliary hook member 58. Hook 58 is supported from yoke 28 in the manner illustrated most clearly in Fig. 2. Yoke 28 is fashioned with a cylindrical socket 60. A screw 62 extends downwardly through socket 60 and engages a threaded boss 64 at the upper end of hook 58. The portion of screw 62 extending through bore 60 is insulated from the yoke by an insulating sleeve 66. The head of screw 62 is retained within a plunger 68 which is also formed of an insulating material. Plunger 68 is slidably arranged in socket 60. A compression spring 70 is arranged within the bore of socket 60 surrounding insulating sleeve 66. The upper end of spring 70 engages the lower face of plunger 68, and the lower end of spring 70 is seated on the bottom wall 72 of socket 60. An insulating washer 74 is arranged between the bottom wall 72 of socket 60 and the boss 64 of hook member 58. Thus, hook member 58 is effectively insulated from yoke 28 and at the same time is biased upwardly towards yoke 28 to a position wherein boss 64 engages the bottom face of washer 74.

Referring now to Fig. 4, it will be noted that hook 58 includes a dished bottom portion 76 which is of substantial width for insuring adequate cross section to conduct the current. The bottom portion 76 and the boss 64 of hook member 58 are interconnected by a vertical leg 78. Leg 78 is fashioned with a lug 80 to the opposite

faces of which the ends 82 of a pair of flexible electrical conducting straps 84 are secured by a screw 86. Screw 86 passes through the ends 82 of straps 84 and the lug 80. These members are clamped together by a nut 88 on the end of screw 86.

Referring now to Figs. 1 and 3, it will be noted that the cap member 22 utilized for securing the casting 18 on the transverse bar 20 is provided with a horizontally disposed, offset lug 90. Lug 90 has a hole 92 extending downwardly therethrough, and the lower face of the lug is counterbored as at 94. A screw 96 extends downwardly through hole 92 with its lower end threaded in a bracket 98. Bracket 98 is fashioned with an upwardly extending cylindrical socket 100 through which screw 96 extends. An insulating sleeve 102 surrounds screw 96 and extends between an insulating disc 104 on the underside of the head of screw 96 and the bottom wall 106 of cylindrical socket 100. Within the counterbore 94, there is press fitted an insulating bushing 108. A compression spring 110 is arranged between the lower end of bushing 108 and the bottom wall 106 of cylindrical socket 100. With this arrangement, it will be observed that bracket 98 is electrically insulated from cap 22 and is normally biased by spring 100 in a direction downwardly and away from cap 22. The casting 18 at the end of carrier 16, not shown in Fig. 1, is held on bar 20 by a plain cap similar to cap 22 but not necessarily provided with a lug 90.

Referring now to Figs. 1 and 5, the manner in which the anode bars 12 are supported on the tank 10 is illustrated. At one side of the tank, the anode bar 12 is mounted on the flange 112 at the upper edge of the tank by a bracket assembly 114. The means for supporting the other anode bar 12 on the tank are not illustrated. Bracket assembly 114 includes a strap 116 formed with a semicylindrical boss 118 intermediate its ends. At one end, strap 116 is clamped to the flange 112 of the tank by means of a hold-down plate and a pair of screws 122 which extend downwardly through plate 120 and the flange 112 of the tank. An electrical conductor in the form of a strap 124 overlies the outer end of strap 116. Insulating pads 126 are arranged one between the underside of hold-down plate 120 and the upper face of conductor strap 124 and the other between the lower face of strap 116 and the upper face of tank flange 112. When the screws 128 are tightened, the strap 116 is rigidly supported on the flange 112; and at the same time, conductor strap 124 is electrically connected with strap 116. The anode bar 12 is secured in the semi-cylindrical boss 118 on strap 116 by means of a cap 130. Cap 130 is held in place by screws 132 provided with nuts 134 at the lower end thereof. Under some conditions, as will be explained more fully hereinafter, anode bar 12 is insulated from strap 116 by means of an insulating sleeve 136.

The inner end of strap 116 is fashioned as a U-shaped saddle portion 138 in which an auxiliary anode rail 140 is clamped by screws 142 and nuts 144. Auxiliary anode rail 140 extends lengthwise of tank 10 at one side thereof as shown in Fig. 5. Strap 116 is dimensioned in size and mounted on the tank so that when the carrier 16 is arranged on the cathode rails 14, auxiliary anode rail 140 is disposed directly below bracket 98. The bracket 98 is provided with a shoe 146 which slidably engages the upper face of auxiliary anode rail 140 and thus insures good electrical contact between the auxiliary anode rail 140 and bracket 98. The other ends of flexible conductor straps 84 are secured to bracket 98 as by screw 148.

In the arrangement illustrated, it will be observed that when carrier 16 is arranged on the cathode rails 14 as illustrated, shoe 146 automatically engages the upper face of auxiliary anode rail 140. Should there be any misalignment between cathode rail 14 and auxiliary anode rail 140, this is compensated for by compression spring 110. This spring normally biases bracket 98 downwardly to a position such that when the carrier 16 is arranged on anode rails 14, spring 100 is compressed and urges shoe 75

146 into good electrical contact with auxiliary anode rail 140.

When the work rack 40 is suspended on the two hook members 30 of the yoke 28 as illustrated, it will be observed that the hook member 58 automatically engages the underside of sleeve 54. As pointed out previously, spring 70 normally biases hook member 58 upwardly. When the transverse bar 38 of rack 40 is engaged on the hook members 30, the underside of sleeve 54 is engaged by the dished bottom portion 76 of hook 58 and spring 70 is thereby compressed to insure good electrical contact between hook member 58 and sleeve 54. Thus, when the carrier 16 is arranged on the cathode rails 14 and the work rack 40 is suspended from the carrier 16 as illustrated, the auxiliary anode 50 is electrically connected with the auxiliary anode rail 140.

If it is desired to apply a different voltage to anodes 48 and 50, then the insulating sleeve 136 around the portions of the anode bar 12 adjacent the auxiliary anode rail 140 are employed. Under such conditions, auxiliary conductor straps 150 are connected to the two anode bars 12. Then at the voltage controlled current source designated 152, which may be a motor generator or rectifiers, the cathode rails would be connected by a conductor 154 with the negative terminal, the straps 150 would be connected to one positive terminal by conductors 156, 158 and the strap 124 would be connected by a conductor 160 to the other positive terminal, the positive terminals being at different controlled voltages. Thus, one voltage is applied to the anodes 48 and a different voltage is applied to the auxiliary anodes 50 on the work racks.

The means for conveying the carriers 16 through successive stations in a plating tank and for lifting them from the last station of one tank and depositing them in the first station of the next tank do not form part of this invention. These means may take any desirable form, those shown in my above mentioned copending applications, for example, and are therefore not illustrated.

Thus, it will be seen that I have provided an auxiliary anode system that is admirably adapted for the automatic type plating machines. The arrangement of this invention enables the mounting of auxiliary anodes on the racks themselves and also permits the application of different controlled voltages to the two sets of anodes. It will also be appreciated that by forming the rack contacting member on the carrier as the hook 58 aligned with the hooks 30, the carriers are adapted for use with automatic loading apparatus.

I claim:

1. In a plating machine of the type wherein rack supported work pieces are conveyed through a plating tank, the racks being suspended from carriers which are slidably supported and in electrical contact with cathode rails and anodes are supported in the plating solution within the tank by means of anode bars extending along the tanks whereby electrical current is caused to flow from the cathode rails through the work carrier to the work pieces and through the solution to the anodes, the improvement which comprises an auxiliary anode carried by the work rack, means insulating the auxiliary anode from said work rack, a contact member on the carrier, means insulating the contact member from said carrier, means responsive to the suspending of the work rack on the carrier to electrically connect the auxiliary anode with the contact member, an auxiliary anode rail within and extending lengthwise of the tank structure of the plating machine, a second contact member on the carrier and arranged to slidably contact the auxiliary anode rail when the carrier is arranged on the cathode rails, means insulating said second contact member from the carrier and means electrically connecting said two contact members on the carrier.

2. The combination called for in claim 1 wherein the rack includes a bar at the upper end thereof, and said carrier includes a pair of hooked members engageable

With said bar to support the rack, said first mentioned means including a sleeve on said bar, means electrically connecting said sleeve to said auxiliary anode, means insulating said sleeve from said bar, and said first contact member on said carrier engaging said sleeve.

3. The combination called for in claim 2 wherein spring means are provided on the carrier for biasing said last mentioned contact member into engagement with said sleeve.

4. In a plating machine of the type wherein rack supported work pieces are conveyed through a plating tank, the racks being suspended from carriers which are slidably supported and in electrical contact with cathode rails and anodes are supported in the plating solution within the tank by means of anode bars extending along the tanks whereby electrical current is caused to flow from the cathode rails through the work carrier to the work pieces and through the solution to the anodes, the improvement which comprises an auxiliary anode carried by the work rack, means insulating the auxiliary anode from said work rack, a contact member movably mounted on the carrier, means insulating the contact member from said carrier, an electrical conducting member insulatively mounted on said rack and connected with said auxiliary anode, means responsive to suspending the work rack on the carrier to bias said contact member into electrical contact with said electrical conducting member, an auxiliary anode rail within and extending lengthwise of the tank structure of the plating machine, a shoe movably mounted on the carrier means insulating said shoe from the carrier, means biasing said shoe into contact with said auxiliary anode rail when the carrier is slidably arranged on the cathode rails and means electrically connecting said contact member with said shoe.

5. In a plating machine of the type wherein rack supported work pieces are conveyed through a plating tank, the racks being suspended from carriers which are slidably supported and in electrical contact with cathode rails and anodes are supported in the plating solution within the tank by means of anode bars extending along the tanks whereby electrical current is caused to flow from the cathode rails through the work carrier to the work pieces and through the solution to the anodes, the improvement which comprises an auxiliary anode carried by the work rack and insulated therefrom, said carrier having a pair of hook members thereon similarly disposed, a third hook member insulatively supported by the carrier and movably mounted thereon, said third hook member being generally aligned with said other two hook members and similarly disposed, means insulatively carried by the rack and connected with the anode engaged by said third hook member when the rack is supported by said other two hook members, an auxiliary anode rail within and extending lengthwise of the tank structure of the plating machine, a shoe on the carrier and arranged to slidably contact the auxiliary anode rail when the carrier is arranged on the cathode rails, means insulating said shoe from the carrier, and means electrically connecting said third hook member and said shoe.

6. A work carrier for a plating machine comprising a support having a pair of spaced apart contact faces for slidably engaging cathode rails of the plating machine, a hook member on the support electrically connected to said contact faces and adapted for suspending a work rack, a contact member on said carrier means insulating said contact member from said hook member and contact faces, said contact member being arranged to engage a portion of a work rack engaged by said hook member, means forming a third contact face on the carrier and insulated from the carrier, said last mentioned means being arranged to engage an anode rail on the tank structure when the carrier is arranged with said pair of contact faces slidably engaging the cathode rails of the plating machine and means electrically connecting said con-

tact member with said means forming said third contact face.

7. A work carrier as called for in claim 6 wherein said contact member comprises a hook member disposed generally in alignment with the first mentioned hook member.

8. A work carrier as called for in claim 7 wherein said second mentioned hook member is movably mounted on the carrier, and spring means biasing said second hooked member in a direction to engage a portion of the rack when the rack is suspended from the first mentioned hook member.

9. A work carrier as called for in claim 8 wherein said means forming said third contact face comprises a contact shoe movably mounted on said carrier and means on said carrier biasing said contact shoe in a direction such that the contact shoe will slidably engage the auxiliary anode rail when the carrier is arranged on said cathode rails.

10. A work carrier on the type adapted to be moved along a pair of cathode rails of a plating machine comprising a support having a pair of spaced apart depending hook members thereon, a third hook member generally aligned with said pair of hook members and spaced intermediate thereof, said third hook member, means insulating said third hooked member from said other hook members, spring means on the carrier for biasing said third hook member in an upward direction, said carrier having a pair of spaced apart contact shoes thereon for slidably engaging the cathode rails of the plating machine, said carrier having a third contact shoe thereon and insulated therefrom, said third contact shoe being movably mounted on said carrier, spring means on said carrier for biasing said third contact shoe in a downward direction, and means electrically connecting the third hook member and the third contact shoe.

11. A work carrier of the type adapted to be moved along a pair of cathode rails of a plating machine comprising a support having a pair of spaced apart depending hook members thereon, one of which is electrically connected to the support and the other electrically insulated from the support, said hook members being generally aligned so that a transverse supporting bar of a work rack is adapted to be engaged therewith to support the rack, said support having a contact shoe thereon, means insulating said contact shoe from the support and means electrically connecting the insulated hook member and the contact shoe.

12. A work carrier as called for in claim 11 wherein said insulated hook member is movably mounted on the support, and spring means on said carrier for biasing said insulated hook member upwardly.

13. A work carrier as called for in claim 11 wherein said contact shoe has a downwardly facing contact face.

14. A work carrier as called for in claim 13 wherein said contact shoe is mounted for vertical movement on said support, and spring means on the carrier for biasing said contact shoe in a downward direction.

15. A work carrier of the type adapted to be moved along a pair of cathode rails of a plating machine comprising a support having a pair of spaced apart depending hook members thereon, each of said hook members having an upwardly facing support surface thereon, a third hook member generally aligned with said pair of hook members and spaced intermediate thereof, said third hook member also having an upwardly facing support surface thereon and being disposed such that when a support member on a work rack is engaged with said upwardly facing support surfaces of said first two mentioned hook members, said support surface of said last mentioned hook member engages a portion of the support member on the rack, means insulating said third hook from said other hook members, means forming a contact face on the carrier, means insulating said last mentioned means from the carrier, said last mentioned means being arranged to engage an anode rail on the tank structure when the carrier is arranged on the cathode rails of

the plating machine and means electrically connecting said third hook member with said means forming said contact face.

16. A work carrier as called for in claim 15 wherein said third hook member is movably mounted on the carrier and said carrier having spring means engageable with said third hook member for biasing the same in an upward direction.

17. The combination called for in claim 15 wherein said last mentioned contact member comprises a third hook member on the carrier.

18. The combination as called for in claim 17 wherein said last mentioned hook member is movably mounted

on the carrier, and spring means on said carrier for biasing said last mentioned hook member into engagement with said sleeve.
